UNITED STATES PATENT OFFICE.

FREDERICK N. MARVICK, OF PINE BLUFF, ARKANSAS.

SILL CONSTRUCTION.

1,346,459.

Specification of Letters Patent. Patented July 13, 1920.

Application filed July 23, 1918. Serial No. 246,376.

To all whom it may concern:

Be it known that I, FREDERICK N. MARVICK, a citizen of the United States, and a resident of Pine Bluff, in the county of 5 Jefferson and State of Arkansas, have invented certain new and useful Improvements in Sill Constructions, of which the following is a specification.

My invention is an improvement in sill 10 constructions, and has for its object to provide a construction of the character specified wherein the heavy wooden sill generally used is replaced by a plurality of pieces of relatively small cross section, thus permitting 15 heart pieces to be used.

In the drawings:

Figure 1 is a section on the line 1—1 of Fig. 2;

Fig. 2 is a section on the line 2—2 of 20 Fig. 1, both views looking in the direction of the arrows adjacent to the respective lines.

In the embodiment of the invention shown in Figs. 1 and 2, the improved sill construction is shown in connection with a brick veneer wall. In this construction a foundation wall is provided, consisting of a base or horizontal portion 1 and a superstructure or vertical portion 2.

30 Suitable ventilators 3 may be provided in the superstructure, and upon the upper surface of the said superstructure is arranged a series of blocks 4, the said blocks being spaced about sixteen inches from center to center, and the long dimension of each block is perpendicular to the plane of the foundation wall. The upper surface of the wall is preferably coated with asphalt or the like, the blocks 4 being arranged on this coating.

40 The sill 5 is composed of superposed 2x4's, and these are held to the foundation wall by means of bolts 6. These bolts 6 have their heads and approximately half of their bodies embedded in the concrete foundation

45 wall, and the sill sections 5 have registering openings through which the bolts are passed, and the bolts are engaged by nuts above the sill section, washers being arranged beneath the nuts as shown. Thus the sill is se-

50 curely held to the foundation wall, and the inner or lining wall 7 of the ship-lap abuts against the outer faces of the sills, the lowermost plank of the said wall 7 resting upon the blocks 4. These blocks are of a length

55 to extend from the inner face of the sill and

the foundation wall to near the inner face of the brick veneer indicated at 8, and it will be noticed that the wall 7 is spaced away from the veneer wall 8, the blocks 4 being of sufficient length to extend from 60 the inner face of the sill 5 beyond the outer face of the wall 7. Just above the blocks 4 is arranged a strip 9, the said strip extending the full length of the wall to catch and hold droppings of mortar from the wall 65 8 which might otherwise fall upon the foundation wall.

The floor which, in the present instance, is shown consisting of a subfloor 10 and a finished floor 11, is laid upon joists 12 70 which, in turn, are laid upon the sills 5, the said joists being so laid that they will be at the blocks 4, as clearly shown in Fig. 2.

The studding 13 also rests upon the sills 5, the said studding being arranged alongside the joists 12 in the usual manner, and the lath and plaster wall 14 is separated from the wall 7 by the studding.

Means is also provided for making the walls vermin proof, that is, for closing the 80 space between the studding, the wall 7 and the wall 13. Strips 14 and 15 of two by four material are arranged between each pair of adjacent joists, the said strips being of a length to abut at their ends the joists, 85 and they are arranged at right angles to each other as shown in Fig. 1, with abutting corners, to form a species of box between the joists, the strips and the wall 7. Within this box is arranged plastic mate- 90 rial capable of hardening, as, for instance, concrete, the said material being indicated at 16, and it will be obvious that the blocks 16 of concrete form a barrier against the passage of vermin, as, for instance, rats, 95 mice and the like, from below the flooring to above the same.

As is known, large pieces of wood, that is, pieces having a relatively large cross section, decay faster than pieces having a relatively small cross section. It is also a fact that wood well ventilated will last longer than wood not so ventilated and that when the wood comes into contact with dampness it soon decays. The upper portion of the 100 foundation wall in Fig. 1 constitutes a sub-sill, and this sub-sill is thoroughly ventilated from every side. The sill being composed of two pieces of relatively small cross section may be made from heart wood 110

clear of sap, and of a lasting wood, as, for instance, cypress or oak. Perfect insulation against dampness is provided, as is also ventilation and protection against vermin.

5 I claim:

In building construction, the combination with the foundation wall and the house wall rising therefrom, of blocks arranged transversely of the foundation wall and resting upon the top thereof with their inner ends flush with the inner face of the foundation wall and their outer ends spaced inwardly from the house wall, a sill laid upon said

blocks and anchored to the foundation wall, said sill having a width less than the length 15 of said blocks whereby its inner face will be flush with the inner ends of the blocks and its outer face disposed inwardly of the outer ends thereof, and a sheathing disposed upon the blocks against the outer face 20 of the sill and spaced from the house wall.

FREDERICK N. MARVICK.
